UNITED STATES PATENT OFFICE.

JOSEPH H. NEAL, OF BALTIMORE, MARYLAND.

BATH-TUB.

962,240.

Specification of Letters Patent. Patented June 21, 1910.

Application filed January 12, 1910. Serial No. 537,588.

To all whom it may concern:

Be it known that I, JOSEPH H. NEAL, a citizen of the United States, residing at Baltimore, in the State of Maryland, have invented certain new and useful Improvements in Bath-Tubs, of which the following is a specification.

This invention relates to cast-metal bath-tubs.

10 One object of my invention is to provide bath tubs with an improved top-roll having therein a water-conduit that shall be formed in the foundry operations of molding and casting, by the use of a sand-core—the said 15 water-conduit to have such novel structural features as will enable the said sand-core to be readily broken up and removed after the casting operations have been completed.

Another object of the invention is to provide 20 a bath-tub with a top-roll water-conduit which will receive its supply of water at the front end of the tub—and said conduit to have such features that the water will flow through the conduit from the said point of 25 supply along both sides of the top-roll without discharging, until it has passed the median line between the front and rear ends of the tub, and then such water while it continues to flow after passing said median line 30 shall freely discharge from the conduit and run down the inner surface of the wall at the rear part of the sides and at the end of the tub.

Another object of the invention is to provide 35 a cast-metal bath-tub with a seat formed at one end of the tub and of metal integral with the tub structure, and also to provide the top-roll of the tub with a water-conduit that shall discharge water into the tub only 40 at that part which is at the sides or around the said seat.

Another object of the invention is to provide 45 a bath-tub with a top-roll water-conduit and to also provide the tub at its front end with a water-receiving chamber which shall be in communication with said water-conduit, whereby the water supply coming from the pipes under pressure will first enter the said chamber where the force of the 50 water will be broken, and then flow from the chamber into the said conduit.

The invention is illustrated in the accompanying drawing in which,—

Figure 1 is a perspective side and top 55 view of the improved bath-tub. Fig. 2 shows on a larger scale, a vertical cross-sec-

tion taken on the line 2—2, of Fig. 1, showing the top-roll and the water-receiving chamber. Fig. 3 shows a cross-section of the top-roll and water-conduit, taken on the line 3—3. Fig. 4 shows a similar section taken on the line 4—4, over the seat.

In making porcelain enameled bath-tubs, the tub is first made of cast-iron in the foundry and is then enameled. Tubbs of the 65 class to which this invention relates are made and enameled as just mentioned.

In this invention the top-roll, C, is of special formation in order to produce a water-conduit, b, having the desired structural 70 features. The bath-tub, A, the conduit, b, and the roll, C, are all integral cast-iron. In molding the top-roll at the foundry to form the conduit, b, a "sand-core" is used, and in order to provide for the removal of 75 the sand-core a slot, d, is formed along the inward side of the roll, C, and at the top of the wall, e, of the bath-tub. This open slot extends entirely around the top of the bath-tub except at the front end. It will 80 be seen by reference to Figs. 1, 3 and 4 of the drawing, that in forming the slot the contour and shape of the upper surface of the top-roll is preserved or may be shaped as preferred and the effect of the slot, d, is 85 to produce on the top roll a lip, f, that projects toward the interior of the tub, but stops short of a vertical line coincident with the inner surface of the tub-walls. For one half of the length of the conduit said 90

lip is directly over a raised edge, g, shown in Fig. 3, at the top of the bath-tub wall, e. The top-roll thus made serves all the purposes and advantages which is served by the ordinary top-roll used on other tubs, 95 and in addition this improved roll with its conduit, b, and open-slot, d, will permit of the sand-core being readily removed, will allow the porcelain enamel to be applied within and will also provide for the flow of 100 water in the conduit as far along as said raised edge, g, extends which is from the front end to a little past a vertical median line, indicated by the letter, x. From the point indicated to the rear end of the tub 105 the conduit is without the raised edge, g, and the shape of the edge at this part is like that shown at, h, in Fig. 4. By this construction the water after flowing past the raised edge, g, at point, x, will continue 110 to flow, but will also freely discharge along the lower edge, h, of the conduit and run

down the inner surface of the wall, *e*, at the rear part of the sides and at the rear end.

In the vertical direction the tub is deeper at the front end than at the rear end, as seen in Fig. 1. The deepest part of the tub is at the lowermost horizontal bottom line, *i*; this deepest part has a rear vertical wall, *k*, which is in vertical alinement with the median line just forward of said point, *x*.
 10 The shallow part of the tub is at the uppermost horizontal bottom line, *j*. This construction forms inside of the tub a seat which is indicated just above the line, *j*. The so-called seat will be of cast metal integral with the tub structure and comprises the entire high part of the tub-bottom at the rear end. The relative position of this "seat" with respect to that part of the water-conduit that has the low edge, *h*, is such
 15 that the water will discharge from the conduit and flow down the side and end walls, *e*, around said seat. By using hot water the walls and seat will be made warm. A person can sit on the seat above high part, *j*, and place his feet in the deeper part at *i*.

A pedestal or standard, *l*, is under the rear end of the tub and supports the same.

At its front end the tub has a water-receiving chamber, *m*, formed integral with the front-end wall, *e*, of the tub; this chamber is constructed with its lower end open in order to remove the sand-core that must be used in molding the chamber. A plate, *n*, closes said lower end.

35 A surface, *C*, same as the top-roll covers the upper end of the water-receiving chamber and below this top surface said chamber has at opposite sides, a suitable opening, *p*, see Fig. 2, and said openings communicate 40 with the water-conduit, *b*. The pipe or pipes, *q*, which lead from the water-supply, enter the said water-receiving chamber. The water from these pipes, *q*, is usually under considerable pressure, and as the water must 45 first enter the chamber, *m*, the force of the water will be broken or lessened, and then with a reduced pressure the water will flow from the chamber, *m*, into the conduit, *b*, of the bath-tub. The waste or discharge of 50 water from the tub takes place through pipe, *r*.

Bath tubs of cast-metal are usually if not always coated with vitreous enamel, and therefore the structural features of this tub have all been designed with reference to the 55 practicability of the parts being enameled.

Having thus described my invention what I claim and desire to secure by Letters Patent is,

1. A cast-iron bath-tub having a hollow 60 top-roll that contains a water-conduit which has directly over the wall of the tub an edge, *g*, higher than the bottom of said conduit—said higher edge confining the water to the conduit and extending from the front end 65 of the tub to a median line between the said front and rear ends, and which conduit from said median line and extending to the rear end of the tub has a low edge, *h*, which permits the water in the conduit to run down 70 the inner surface of the tub-wall.

2. A cast-metal bath-tub whose bottom is divided into two distinct parts—the front-end part being in a lower horizontal plane than the rear-end part which latter being 75 higher serves as a seat, in combination with a hollow top-roll that contains a water-conduit provided with an open slot along the inward side of the roll—said conduit having a raised edge, *g*, which confines the water to 80 the conduit and extends from the front-end of the tub back to a point above the front of said seat, the conduit from said seat back to the rear-end of the tub having a low edge, *h*, which permits the water to flow from the 85 conduit down the sides of the walls around and onto the seat.

3. A cast-metal bath-tub provided with a seat at the rear-end of the tub—said seat being integral with the metal of the tub, and 90 also provided with a top-roll water-conduit which receives the water-supply at the front end and has means by which it discharges water into the tub only at that part which is at the sides of the seat or around the seat. 95

In testimony whereof I affix my signature in presence of two witnesses.

JOSEPH H. NEAL.
